UNITED STATES PATENT OFFICE.

ROBERT MITCHELL, OF ATLANTA, GEORGIA.

MOSQUITO-CANOPY.

SPECIFICATION forming part of Letters Patent No. 338,428, dated March 23, 1886.

Application filed June 17, 1885. Serial No. 162,966. (No model.)

To all whom it may concern:

Be it known that I, ROBERT MITCHELL, of Atlanta, in the county of Fulton and State of Georgia, have invented a new and Improved 5 Mosquito-Canopy, of which the following is a full, clear, and exact description.

My invention relates to mosquito-canopies, and more particularly to the tops of canopies for beds; and a special object of the invention 10 is to facilitate the clearing of the insects from the space inclosed by the canopy, and by means of simple, durable, and efficient devices.

The invention comprises a mosquito-canopy top adapted to support the sides of the 15 canopy fabric and connected to a hanger or arm support, and provided with opposite hinged lids or frames, the side arms of which engage each other, so that by drawing on one arm both lids will be opened for escape of the 20 insects that are in the space inclosed by the canopy.

The invention consists, also, in particular constructions and combinations of parts of the canopy, all as hereinafter fully described and 25 claimed.

Reference is to be had to the accompanying drawings, forming part of this specification, in which similar letters of reference indicate corresponding parts in all the figures.

Figure 1 is a side view of my improved 30 canopy, with the drooping sides of the netting indicated in dotted lines, and the top open. Fig. 2 is a central transverse sectional elevation of the same. Fig. 3 is a plan view of the canopy-top closed and partly broken away. Fig. 4 is an enlarged cross-sectional endwise 35 view of the canopy-top in closed condition; and Fig. 5 represents a side view of the canopy-top as arranged upon a bar hinged and 40 braced to a staff adapted for attachment to a bedstead, and showing the top open.

The letter A indicates a frame of light metal or wood, shown square or rectangular in general form, but which may be made round, oval, 45 or of any other preferred form.

At B is shown the side mosquito-netting fabric, which is attached in any approved way to the frame A, so as to droop therefrom around a bedstead or other article of furniture or 50 thing to be inclosed for protection against insects.

The frame A may be suspended by its hanger C from a cord, C', fixed overhead, as in Figs. 1 and 2, or may be fixed to a bar, D, hinged at d to the head of a post, E, adapted 55 to be attached to the head-board of a bedstead, or the back of a chair or other article of furniture, braces at e e being provided, so that the canopy-top may be held up for use, and the braces are pivoted to the bar D and post 60 E, and so attached to each other as to allow the entire head or top frame, A, with its fabric B, to be folded down when out of use, or for inclosure within a folding bed, to the head-board of which the post E may be attached. 65

The hanger C (shown only in Figs. 1 to 4,) consists preferably of a couple of strong wires, c c, twisted together for a distance both ways from the center of the hanger, where the suspension-cord C' is attached, and near each end 70 the wire strands c c are branched opposite ways and bent downward and inward to form pins c' c', which are passed through holes in the frame A, to give a substantial support to the frame at each end of the frame. 75

The inwardly-projecting pins c' c' are sufficiently long to form pivots to the opposite side frames, F G, which have eyes f g, respectively, fitted on the pivots on which the side frames may swing up from the top frame, A, 80 upon which they fall normally by their own weight.

A suitable mosquito-netting fabric, H, is stretched across the canopy-top, and is secured to the frames F G, so that when these 85 frames are closed the fabric H, with the fabric B, will form a complete close canopy, as in Figs. 3 and 4, to exclude insects, and when the frames F G are swung open on their pivots c' c', as in Figs. 1, 2, and 5, any insects which may 90 have found their way inside the canopy may readily be driven from the open top of the canopy without requiring the persons occupying the bed to leave it and take the canopy down and turn it inside out to clear it of the 95 insects, as must be done with canopies otherwise arranged.

To provide for opening the canopy-top frames F G conveniently, I have extended one of the side arms of the frame G, and bent it 100 upon itself to form an elongated open loop or eye, I, and have extended the adjacent side

arm of the frame F, forming a rod, J, which is bent to pass through the loop I, and is extended toward the center of the canopy-top, and has a cord, K, attached to its end, which 5 hangs down within reach of a person under the canopy.

It is evident that by pulling on the cord K that part of rod J which rests in the loop I will be swung down and will swing down the loop, so that the opposite frames, F G, will simultaneously be opened, the loop I being of proper length to limit the swing of the arm J, so that the frames F G will not swing up quite to a full opening, and hence will fall by 5 gravity when the pull on the cord is relaxed. It only is necessary to draw on the cord to open the frames F G, and consequently the netting H at both sides of the top frame, A, and to hold the frames open for a sufficiently long o time to drive the insects from the canopy, and at the same time secure better ventilation, and on slackening the cord the top will close automatically.

When the canopy-top is supported by the 5 bar D and the post E, the bar will pass across the top of the frame A at its center, as indicated in dotted lines in Fig. 4.

If preferred, the frame A may be made of heavy wire, as are the frames F G shown, but o any suitable material may be employed in making the several parts of the canopy-top.

Having thus described my invention, what I claim as new, and desire to secure by Letters Patent, is—

5 1. A mosquito-canopy top comprising a frame, A, adapted to support the sides of

the canopy fabric, opposite lids hinged to frame A to close it, a loop, I, on one lid, and a rod, J, on the other lid engaging loop I, substantially as described, whereby both lids will 40 be opened simultaneously by drawing on rod J, as herein set forth.

2. A mosquito-canopy top comprising a frame, A, adapted to support the sides of the canopy fabric, and connected to a suitable 45 support, opposite frames, F G, pivoted to frame A and covered by netting fabric H, a loop, I, on frame G, and a rod, J, on frame F, engaging loop I, substantially as herein set forth.

3. A mosquito-canopy top comprising a 50 frame, A, adapted to support the sides of the canopy fabric, and connected to a suitable support, opposite frames, F G, pivoted to frame A and covered by netting fabric H, a loop, I, on frame G, a rod, J, on frame F, engaging 55 loop I, and a pull-cord, K, connected to rod J, substantially as herein set forth.

4. The combination, in a mosquito-canopy, of the frame A, adapted to support the sides of the canopy fabric, a hanger, C, having 60 branched arms c c, connecting with opposite ends of the frame A, and having inturned ends forming pivot-pins c' c', opposite side frames, F G, pivoted on said pins and covered by netting H, a loop, I, on frame G, a 65 rod, J, on frame F, engaging loop I, and a pull-cord, K, connected to rod J, substantially as herein set forth.

ROBT. MITCHELL.
